TRAP CIRCUIT CONTROL FOR RAILWAY SIGNALS

Filed April 5, 1947

UNITED STATES PATENT OFFICE

2,448,570

TRAP CIRCUIT CONTROL FOR RAILWAY SIGNALS

Earl M. Allen, Pittsburgh, Pa., assignor to The Union Switch & Signal Company, Swissvale, Pa., a corporation of Pennsylvania

Application April 5, 1947, Serial No. 739,569

6 Claims. (Cl. 246—41)

1

My invention relates to trap circuit control for railway signals, and particularly to an arrangement of circuits for providing continuous control of railway signals by a train on a stretch of track which includes a dead section in an otherwise continuous series of track circuited sections.

In some situations such, for example, as where one railway crosses another railway which has a plurality of tracks, the first railway has a section through the multiple track crossing which cannot be provided with a track circuit and which is longer than the shortest train which may be run on the first railway. It is therefore possible for a short train to occupy this section, known as a dead section, at the crossing, without shunting any track circuit. In such a situation, it is common practice to use an arrangement of circuits to provide what is known as trap circuit control, through which a signal for the first railway is controlled by a train on the first railway approaching the crossing to indicate stop when the train passes the signal, and to continuously indicate stop while the train is wholly on the dead section and until the train has passed through the first section beyond the dead section.

One feature of my invention is the provision of a directional trap circuit arrangement, in which a trap circuit stick relay, which becomes deenergized when a train moves from an approach section wholly onto a dead section, can again become energized only in response to the train passing from the dead section into an adjacent approach section and cannot become energized by a second train entering the opposite end of an adjacent approach section.

Another feature of my invention is the provision of circuits for controlling a trap circuit stick relay arranged so that the trap circuit stick relay will become deenergized by only a train that is short enough to be wholly on the dead section. A train that is long enough that, while it is passing over the dead section, it extends over onto one of the adjacent sections, will not deenergize the trap circuit stick relay.

I shall describe one form of apparatus embodying my invention, and shall then point out the novel features thereof in claims.

The accompanying drawing is a diagrammatic view showing one form of apparatus embodying my invention, in which each of the two track sections adjoining the ends of a dead section is provided with a track circuit including a track

2

relay connected across its end which adjoins the dead section, and also including a second track relay connected around an insulated joint in one of its rails; and in which directional control of a trap circuit stick relay is effected by these track relays and by a slow pick-up and slow release relay for each track circuit controlled by its track relays.

Similar reference characters refer to similar parts in the drawing.

Referring to the drawing, a single track railway is shown crossing a multiple track railway designated by the reference character L. Rails 1 and 1a of the single track railway are divided by insulated joints 2 to form a section a—b adjoining one end of a dead section b—c, and a second section c—d adjoining the opposite end of dead section b—c. The rail of one side of each of the sections a—b and c—d is also divided by an insulated joint 3 to form subsections 5T and A5T of section a—b, and subsections 6T and A6T of section c—d.

Section a—b is provided with a track circuit including a track relay A5R connected across the end of section a—b which is adjacent one end of the dead section b—c, and including a suitable source of current such as a battery 4 connected across the opposite end of the section, and also including a second track relay 5R connected around its insulated joint 3. Section c—d is provided with a similar track circuit including a track relay A6R connected across the end of section c—d which is adjacent the opposite end of the dead section b—c, and including a battery 4 connected across the opposite end of the section, and also including a second track relay 6R connected around its insulated joint 3.

A signal, designated by the reference character 5S, is located adjacent the battery end of section a—b for governing traffic movements towards the right, as shown in the drawing, which I shall assume is the eastbound direction. A second signal 6S is located adjacent the battery end of section c—d for governing traffic movements in the opposite or westbound direction. Signals 5S and 6S may be of any suitable design such, for example, as the well-known searchlight type.

A slow pick-up and slow release relay, designated by the reference character 5P, is controlled by relays A5R and 5R. A second slow pick-up and slow release relay 6P is similarly controlled by relays A6R and 6R.

A trap circuit stick relay, designated by the reference character TPS, is controlled by the

track relays and by the slow pick-up and slow release relays. An impedance r is connected in multiple with the winding of relay TPS in order to make this relay slow in releasing.

Having described, in general, the arrangement of the various parts of apparatus embodying my invention, I shall now describe the circuits and operation in detail.

As shown in the drawing, all parts of the apparatus are in the normal condition, that is, the track sections are unoccupied, and therefore track relays 5R, A5R, A6R and 6R are energized; relays 5P, 6P and TPS are also energized; and signals 5S and 6S are displaying a proceed indication.

The circuit by which relay 5P is energized passes from terminal B of a suitable source of current, through the front point of contact 7 of relay A5R, and the winding of relay 5P to terminal N of the same source of current. Relay 6P is energized by a similar circuit passing from terminal B, through the front point of contact 7 of relay A6R, and the winding of relay 6P to terminal N.

Relay TPS is energized by a stick circuit passing from terminal B, through the front point of contact 9 of relay A6R, contact 10 of relay 6P, front point of contact 11 of relay A5R, contact 12 of relay 5P, contact 13 of relay TPS, and the winding of relay TPS in multiple with impedance r to terminal N.

The circuit by which signal 5S is controlled to display a proceed indication includes contacts 14, 15, 16, 17 and 18 of relays 6R, A6R, A5R, 5R and TPS, respectively, and the mechanism of signal 5S to terminal N. The circuit by which signal 6S is controlled to display a proceed indication includes contacts 19, 20, 21, 22 and 23 of relays TPS, 5R, A5R, A6R and 6R, respectively, and the mechanism of signal 6S to terminal N.

I shall assume that an eastbound train which is shorter than dead section b—c approaches signal 5S. This train, upon entering section a—b, deenergizes relays 5R and A5R. Relay A5R, upon becoming deenergized, opens, at the front point of its contact 7, the circuit previously traced for energizing relay 5P. A second circuit is now completed for energizing relay 5P, however, passing from terminal B, through the back point of contact 7 of relay A5R, back point of contact 8 of relay 5R, and the winding of relay 5P to terminal N. Relay 5P, on account of being slow releasing, does not permit its contact 12 to open during the interval between the opening of the first circuit and the closing of the second circuit for energizing this relay.

Relay A5R, upon becoming deenergized, opens, at the front point of its contact 11, the stick circuit previously traced for relay TPS, and then closes, at the back point of its contact 11, a second stick circuit for relay TPS passing from terminal B, through the front point of contact 9 of relay A6R, contact 10 of relay 6P, back point of contact 11 of relay A5R, contact 13 of relay TPS, and the winding of relay TPS in multiple with impedance r to terminal N. Relay TPS, on account of being slow releasing, does not permit its front contacts to open during the interval between the opening of the front point of contact 11 of relay A5R and the closing of the back point of this contact.

With relays A5R and 5R deenergized, the circuit for signal 5S is now open at contacts 16 and 17, respectively, causing signal 5S to display the stop indication. Likewise, contacts 20 and 21 of relays 5R and A5R, respectively, are open in the

circuit for controlling signal 6S, and therefore the arm of signal 6S will now also display the stop indication.

When the rear end of the train passes insulated joint 3 of section a—b, relay 5R becomes energized, thereby completing a pick-up circuit for relay TPS, this circuit passing from terminal B, through the back point of contact 7 of relay A5R, front point of contact 8 of relay 5R, and the winding of relay TPS in multiple with impedance r to terminal N. Relay 5R, upon becoming energized, opens, at the back point of its contact 8, the second circuit traced for energizing relay 5P, and, therefore, relay 5P becomes deenergized.

When the rear end of the train leaves section a—b, relay A5R again becomes energized, thereby opening, at the back point of its contact 7, the pick-up circuit previously traced for relay TPS and opening, at the back point of its contact 11, the second stick circuit traced for relay TPS. Relay 5P is now again energized by the circuit first traced for this relay through the front point of contact 7 of relay A5R. On account of relay 5P being slow to pick up, the front contacts of relay TPS will open between the time of the opening of contact 11 of relay A5R at its back point and the closing of contact 12 of relay 5P. With relay TPS now deenergized, the circuits for signals 5S and 6S remain open at contacts 18 and 19, respectively, of this relay while the train is entirely on dead section b—c.

When the front end of the train enters subsection A6T, relay A6R becomes deenergized, thereby opening, at the front point of its contact 7, the circuit previously traced for relay 6P, causing relay 6P to become deenergized. With relay A6R deenergized, a second pick-up circuit is now completed for relay TPS, this circuit passing from terminal B, through the back point of contact 7 of relay A6R, front point of contact 8 of relay 6R, and the winding of relay TPS and impedance r to terminal N. A third stick circuit is now completed for relay TPS, this circuit passing from terminal B, through the back point of contact 9 of relay A6R, contact 13 of relay TPS, and the winding of relay TPS and impedance r to terminal N. With relay A6R deenergized, the circuits for signals 5S and 6S are now open at contacts 15 and 22, respectively, of relay A6R.

When the front end of the train enters subsection 6T, relay 6R becomes deenergized, thereby opening the second pick-up circuit previously traced for relay TPS, which however now remains energized by its third stick circuit previously traced. A second circuit is now completed for energizing relay 6P, this circuit passing from terminal B, through the back point of contact 7 of relay A6R, the back point of contact 8 of relay 6R, and the winding of relay 6P to terminal N. With relay 6R deenergized, the circuits for signals 5S and 6S are now open at contacts 14 and 23, respectively, of relay 6R as well as at contacts 15 and 22 of relay A6R.

When the train leaves section c—d, relays A6R and 6R again become energized. The second circuit traced for energizing relay 6P is thereby opened, and the first circuit traced for this relay is then again closed. The third stick circuit traced for relay TPS is opened at the back point of contact 9 of relay A6R, and the first stick circuit traced for this relay is again closed through the front point of contact 9 of relay A6R. With all track relays and relay TPS now energized, the portions of the circuits shown for controlling sig-

nals 5S and 6S are again closed, as previously described.

I shall next assume that, as before, a short eastbound train moves through section *a*—*b* onto dead section *b*—*c*, and that it stops wholly on section *b*—*c*. I shall assume further that the train now backs out of section *b*—*c*.

When the rear end of the train enters subsection 5T, relay A5R becomes deenergized, thereby opening, at the front point of its contact 7, the circuit first traced for energizing relay 5P, and causing relay 5P to become deenergized. The first pick-up circuit traced for relay TPS is now completed through the back point of contact 7 of relay A5R, and hence relay TPS becomes energized. The second stick circuit traced for relay TPS through the back point of contact 11 of relay A5R is then also again closed.

When the rear end of the train enters subsection 5T, relay 5R becomes deenergized, thereby opening the first pick-up circuit traced for relay TPS which, however, remains energized by its second stick circuit. Relay 5P is now energized by its second circuit through the back points of contacts 7 and 8 of relays A5R and 5R, respectively.

When the train leaves section *a*—*b*, relays A5R and 5R again become energized, and relay 5P is now again energized by the circuit first traced for this relay through the front point of contact 7 of relay A5R. The second stick circuit traced for relay TPS is now opened and the first stick circuit traced for this relay is again closed. With all track relays and relay TPS now energized, the portions of the circuits shown for signals 5S and 6S are again closed and, therefore, all parts of the apparatus are again in the normal condition.

I shall again assume that a short eastbound train moves through section *a*—*b*, and that it stops wholly on section *b*—*c*, causing relay TPS to be deenergized, as previously described. I shall assume further that a following eastbound train, although attempting to stop in response to the stop indication displayed by signal 5S, actually does not succeed in getting stopped until its front end has entered subsection 5T. The first circuit traced for relay 5P will now be opened and its second circuit will be closed. Both the pick-up circuits previously traced for relay TPS remain open, and therefore relay TPS does not now become energized.

It follows that relay TPS, after being deenergized when a short train moves wholly onto section *b*—*c*, can again become energized only in response to a train moving from section *b*—*c* into section *a*—*b* or *c*—*d*, and not by a second train entering either section *a*—*b* or *c*—*d* from the opposite end.

I shall now assume that an eastbound train which is longer than dead section *b*—*c* moves through section *a*—*b* into section *b*—*c*. Since the train is longer than section *b*—*c*, its front end will enter section *c*—*d* before the rear end leaves section *a*—*b*. The second pick-up circuit for relay TPS is therefore closed while its front contacts are still closed by its second stick circuit or its first pick-up circuit, and hence relay TPS does not become deenergized. When the train leaves section *a*—*b* and continues through section *c*—*d*, the various parts of the apparatus operate as previously described when a short train moves through section *c*—*d*.

If, instead of proceeding through section *c*—*d*, the long train, after its front end has entered subsection 6T, stops, and then backs past sig-

nal 5S, relay TPS will continue energized. After the train leaves section *c*—*d*, all parts of the apparatus will operate as previously described when a short train backs through section *a*—*b*.

5 Although I have herein shown and described only one form of apparatus embodying my invention, it is understood that various changes and modifications may be made therein within the scope of the appended claims without departing 10 from the spirit and scope of my invention.

Having thus described my invention, what I claim is:

1. In a control arrangement for a trap stick relay in a railway signal control system for a 15 stretch of railway track divided into a first and a second section and also a dead section between said first and second sections, the combination comprising, an insulated joint in one side of each of said first and second sections, a track circuit for each of said first and second sections each including a track relay connected across the rails of the end of its section which is adjacent said dead section and including a source of current connected across the rails of the opposite end of its section and also including a second track relay connected around the said insulated joint in one side of its section, a first and a second pick-up circuit for said trap stick relay one of which is controlled by a back contact of the first track 20 relay and by a front contact of the second track relay for one of said track circuits and the other of which is similarly controlled by the track relays for the other track circuit, a slow pick-up and slow release relay for each of said track circuits each having an energizing circuit controlled by a front contact of the first track relay for its section and each also having a second energizing circuit controlled by back contacts of both track 25 relays for its section, a stick circuit for said trap stick relay controlled by front contacts of both said slow pick-up and slow release relays and by front contacts of both of said first track relays, a second stick circuit for said trap stick relay controlled by a back contact of the first track 30 relay for one of said sections, and a third stick circuit for said trap stick relay controlled by a back contact of the first track relay for the other section.

2. In a control arrangement for a trap stick relay in a railway signal control system for a 35 stretch of railway track divided into a first and a second section and also a dead section between said first and second sections, the combination comprising, an insulated joint in one side of each of said first and second sections, a track circuit for each of said first and second sections each including a track relay connected across the rails of the end of its section which is adjacent said dead section and including a source of current connected across the rails of the opposite end of its section and also including a second track relay connected around the said insulated joint in one side of its section, a slow pick-up and slow release relay for each of said track circuits, means 40 for each track circuit controlled by a front contact of its first track relay or by back contacts of both its track relays for energizing its slow pick-up and slow release relay, means controlled by a train approaching said dead section through either said first or said second section for retaining said trap stick relay energized, means controlled by the slow pick-up and slow release relay for each track circuit for deenergizing said trap stick relay when a train passes from 45 its section into said dead section, and means

controlled by the first track relay for each of said track circuits for again energizing said trap stick relay when a train enters its section from said dead section.

3. In a control arrangement for a trap stick relay in a railway signal control system for a stretch of railway track divided into a first and a second section and also a dead section between said first and second sections, the combination comprising, an insulated joint in one side of each of said first and second sections, a track circuit for each of said first and second sections each including a track relay connected across the rails of the end of its section which is adjacent said dead section and including a source of current connected across the rails of the opposite end of its section and also including a second track relay connected around the said insulated joint in one side of its section, means controlled by the first track relay for each track circuit in response to a train in its section approaching said dead section for retaining said trap stick relay energized, means controlled by both track relays for each track circuit in response to a train moving from its section into said dead section for deenergizing said trap stick relay, and means controlled by both track relays for each track circuit in response to a train moving into its section from said dead section for again energizing said trap stick relay.

4. In a control arrangement for a trap stick relay in a railway signal control system for a stretch of railway track divided into a first and a second section and also a dead section between said first and second sections, the combination comprising, an insulated joint in one side of each of said first and second sections, a track circuit for each of said first and second sections each including a track relay connected across the rails of the end of its section which is adjacent said dead section and including a source of current connected across the rails of the opposite end of its section and also including a second track relay connected around the said insulated joint in one side of its section, and means controlled by said track relays for retaining said trap stick relay energized while a train is approaching said dead section and for deenergizing

said trap stick relay when a train moves from either of said first and second sections into said dead section and also for again energizing said trap stick relay when a train moves from said dead section into either said first or said second section.

5. In a control arrangement for a trap stick relay in a railway signal control system for a stretch of railway track divided into a first and a second section and also a dead section between said first and second sections, the combination comprising, a track circuit for each of said first and second sections, means controlled by said track circuits in response to a train approaching said dead section for retaining said stick relay energized, means controlled by said track circuits in response to a train moving from said first or said second section into said dead section for deenergizing said trap stick relay, and means controlled by said track circuits in response to a train entering said first or said second section from said dead section for again energizing said trap stick relay.

6. In a control arrangement for a trap stick relay in a railway signal control system for a stretch of railway track divided into a first and a second section and also a dead section between said first and second sections, the combination comprising, a slow pick-up and slow release relay for each of said first and second sections energized when the associated section is unoccupied, means responsive to a train in each of said first and second sections approaching said dead section for retaining said trap stick relay energized, means responsive to a train in each of said first and second sections approaching said dead section for at first energizing and then deenergizing the associated slow pick-up and slow release relay, means controlled by each of said slow pick-up and slow release relays for deenergizing said trap stick relay when a train moves from the associated first or second section into said dead section, and means responsive to a train entering either of said first or second sections from said dead section for again energizing said trap stick relay.

EARL M. ALLEN.
